DAMPING DEVICE FOR RAILWAY TRUCKS

James C. Settles, Columbus, Ohio, assignor to The Buckeye Steel Castings Company, Columbus, Ohio

Application March 11, 1946, Serial No. 653,582

12 Claims. (Cl. 105—197)

1

This invention pertains to railway trucks and especially to a novel damping device for such trucks.

One of the objects of the invention is to provide a device of this character so constructed that the parts may be readily assembled in, or removed from, the bolster of the truck.

Another object is to provide damping means, the main parts of which may be of cast metal.

The above, as well as various other objects, will become apparent from the following description considered in connection with the accompanying drawings which illustrate an exemplary form of the invention.

In the drawings:

Fig. 1 is a side elevation, partly in longitudinal vertical section, of a portion of a railway truck in which the invention is embodied.

Fig. 2 is a transverse vertical sectional view on the line 2—2 of Fig. 1, but with most of the bolster end in side elevation and with the wedge shoe in its pocket at the near side of the bolster.

Fig. 3 is a horizontal sectional view taken on the line 3—3 of Fig. 1 with the right wedge shoe removed from its pocket to facilitate illustration.

Fig. 4 is a side elevation of one end portion of the bolster without the wedge shoe applied, in order to show the construction of the bolster pocket.

Fig. 5 is a side elevational view of the bridge member.

Fig. 6 is a plan view of the bridge member.

Fig. 7 is a sectional view taken on the line 7—7 of Fig. 6.

Fig. 8 is a side elevational view of one wedge shoe.

Fig. 9 is an elevational view of the friction face of one of the wedge shoes.

Although the invention is illustrated as embodied in a typical four-wheel truck with a truss-type side frame, the damping means is equally applicable to other types of trucks, as will be evident from the following description.

Referring to the drawings, 5 designates a truss-type side frame having a bolster opening 6 for the reception of a bolster end 7, which has top and bottom walls. Housed within the bolster end is a centrally located vertically disposed spring 8 which yieldingly supports a spring cap or bridge 9. The latter is provided at its opposite sides with outwardly projecting portions 10 which extend toward the opposite sides of the bolster and terminate in downwardly diverging extremities 11 having inclined upper surfaces 12, slidably contacting similarly inclined surfaces 13, arranged at the inner sides and at the lower

2

halves of wedge shoes 14. Immediately above the inclined surfaces 13, each wedge shoe is provided with a transversely concaved and inclined upper surface 15 and the surfaces 13 and 15 are so arranged that they converge toward the longitudinal median line of the bolster. The surfaces 15 are so positioned as to bear against complementary inclined surfaces 16 which form the upper webs or back walls of wedge-receiving pockets 17, located in the opposite sides of the bolster. Outwardly of the inclined surfaces 13 and 15, each wedge is formed with a vertical friction surface 18 bearing against a wear plate 19, secured to the web 20 of the side frame column 21.

As explained hereinafter, the spring 8 is arranged to move upwardly with the bolster, and from the above description, it is evident that the upward pressure of the spring forces the spring cap 9 upwardly, which, in turn, moves the wedges upwardly and in opposite directions, against the side frame columns to produce frictional resistance to control relative movement between the side frame and the bolster.

It is evident that wider variations in the inclinations of the inclined surfaces can be made, even to the extent of making either the upper surface 15 or the lower surface 13 of the wedge shoe and its respective cooperating surface, horizontal with no change in the fundamental operation of the device, except one of amount of friction produced for a given force in spring 8.

The construction is such that the parts can be readily assembled in the bolster end before the bolster is applied to the side frame. Spring cap 9 is first inserted into the bolster through opening 22, communicating with pocket 17. The wedges 14 are then inserted in the pockets 17 and positioned inwardly and downwardly as far as possible, in which position, horizontal holes 23 of the wedges are in alignment with similar holes 24 formed in the end walls 25 of the bolster wedge pockets. Pins (not shown) are then inserted in the aligned holes to hold the wedges in their retracted position until after the bolster has been applied to the side frame. The spring 8 is next applied through an opening 26 in the bottom of the bolster and afterwards spring supporting plate 27 (forming part of the bottom wall of the bolster) is introduced into the bottom hole beneath the spring. The latter may be compressed by any convenient means, for instance, by the use of a bolt (not shown) inserted through apertures 28, 29 and 30, provided for the purpose in the spring supporting plate, spring cap and top of the bolster, respectively.

55 The bolster may be applied to the side frame

and the truck operated with the bolt in place, or if preferred, the bolt may be removed after a pin or cotter has been inserted in each of the holes 31, provided in lugs 32 which project from diametrically opposite sides of the plate 27 and are adapted to extend through notches or slots 33, communicating with the hole 26 in the bottom of the bolster.

The wedge retaining pins are withdrawn from the holes 23 and 24 after the bolster has been applied to the side frame and lowered on to load supporting spring coils 34. The cotters may be left in holes 31 to retain the plate 27 in position when the bolster is later raised for shimming the truck or other service operations, such as changing the load carrying springs 34.

The hole occupied by the plate 27 is preferably countersunk and the plate is provided with an offset portion or circular flange 35 (Fig. 2), adapted to underlie and overlap a similar co-operating offset portion 36 formed by the bottom of the bolster and surrounding the hole 26. When the cooperating surfaces thus provided are drawn into contact by any of the above-described means, the bottom surface 37 of plate 27 is in the same horizontal plane as the bottom surface 38 of the bolster, and these surfaces form a continuous surface for supporting the bolster on the load supporting springs 34. In service, when the truck carries a load, the pressure of the underlying spring 34 against the bottom of the plate 27, is greater than the pressure of spring 8 against the top of that plate, and the above mentioned overlapping portions 35 and 36 function to transmit load from the bolster to the spring 34.

If preferred, spring 8 may be compressed when assembling the truck by merely lowering the bolster on springs 34 and applying load to the bolster when spring 8 and plate 27 are in their un-compressed positions. Cotters can then be applied to holes 31 to hold the spring 8 in compressed position for convenience when the bolster is raised during possible later servicing of the truck.

From the above description, it is evident the entire damping means may be inverted in the bolster, if preferred, so that the spring 8 is applied from the top of the bolster and the spring cap member 9 serves as a spring seat and forces the wedges 14 downwardly and outwardly against the side frame columns 21. The functioning of such an inverted device would be fundamentally the same as that illustrated and described above.

While I have disclosed what I now consider to be a preferred embodiment of the invention in such manner that the same may be readily understood by those skilled in the art, I am aware that changes may be made in the details illustrated and described without departing from the spirit of the invention, as expressed in the following claims.

What I claim and desire to secure by Letters Patent is:

1. In a railway truck, a side frame having a bolster opening therein, guide columns defining the sides of said opening, a bolster having an end portion extending into the bolster opening, top and bottom walls on the end portion of the bolster, resilient means supporting the end portion of the bolster on the side frame, said end portion of the bolster having pockets in opposite sides thereof, a web carried by the bolster having an upwardly and outwardly inclined surface forming the top back wall of one pocket, a web carried by the bolster having an upwardly and outwardly in-

clined surface forming the top back wall of the other pocket, a bridge member horizontally disposed between the top and bottom wall of the bolster, a downwardly and outwardly inclined surface carried by one end of the bridge member within one pocket, a downwardly and outwardly inclined surface carried by the other end of the bridge member within the other pocket, a wedge shoe within each of said pockets engaging the associated guide columns, two angularly related surfaces on each wedge shoe with one angular surface engaging the inclined surface at one end of the bridge member and the other angular surface engaging the inclined surface on the web of the bolster, a helical spring within the bolster engaging an intermediate portion of the bridge member at its upper end and the bottom wall of the bolster at its lower end, said bridge member having an opening therein aligned with the axis of the spring, the top wall of the bolster having an opening therein aligned with the opening in the bridge member, the bottom wall of the bolster having an opening therein aligned with the axis of the spring, and said openings being adapted to receive a bolt to compress said spring and retract the bridge member from a position urging the shoes into engagement with the guide columns.

2. In a railway car truck, a side frame having a bolster opening therein, guide columns defining the sides of said opening, a bolster having an end portion extending into said opening, resilient means supporting the bolster on the side frame, top and bottom walls on the end portion for the bolster, said bottom wall having an opening therein, a helical spring of less diameter than said opening arranged within the bolster, a plate closing said opening in the bottom wall of the bolster and forming a seat for said spring, a bridge member within the bolster engaged at its intermediate portion by the upper end of said spring and urged upwardly by the spring, downwardly inclined end portions carried by said bridge member, outwardly inclined surfaces carried by the bolster, said bolster having pockets therein adjacent the ends of said bridge member, wedge shoes within said pockets, a sloping surface on each shoe engaging the associated inclined surface of the bolster, a second sloping surface on each shoe engaged by the associated inclined end portion on the bridge member to urge the shoes out of said pockets, said plate having an opening therein aligned with the axis of said spring, and said bridge having an opening therein aligned with the opening in the plate for receiving a bolt to compress said spring.

3. In a railway truck, a side frame having a bolster opening therein, guide columns defining the sides of said opening, a bolster having an end portion extending into the bolster opening, spaced top and bottom walls forming a part of the end portion of the bolster, resilient means supporting the bolster on the side frame, said end portion of the bolster having pockets in opposite sides thereof, an upwardly and outwardly inclined surface forming the top wall of one pocket, an upwardly and outwardly inclined surface forming the top wall of the other pocket, a bridge member disposed between the top and bottom wall of the bolster, a downwardly and outwardly inclined surface carried by one end of the bridge member within one pocket, a downwardly and outwardly inclined surface carried by the other end of the bridge member within the other pocket, a wedge shoe within each of said

pockets engaging the associated guide columns, two angular surfaces on each wedge shoe for engaging the inclined surface at one end of the bridge member and the inclined surface at the top of one pocket, a helical spring within the bolster engaging an intermediate portion of the bridge member at its upper end, said bridge member having an opening therein aligned with the axis of the spring, the top wall of the bolster having an opening therein aligned with the opening in the bridge member, the bottom wall of the bolster having an opening larger than the diameter of said spring, a plate closing the opening in the bottom wall of said bolster forming a spring seat for the lower end of said helical spring, means maintaining the plate in position closing said opening and compressing said spring to urge the bridge member upwardly, and said plate having an opening therethrough aligned with the axis of said spring.

4. In a railway truck, a side frame having a bolster opening therein, guide columns defining the sides of said opening, a bolster having an end portion extending into the bolster opening, spaced top and bottom walls forming a part of the end portion of the bolster, resilient means supporting the bolster on the side frame, said end portion of the bolster having pockets in opposite sides thereof, an upwardly and outwardly inclined surface forming the top wall of one pocket, an upwardly and outwardly inclined surface forming the top wall of the other pocket, a bridge member disposed between the top and bottom wall of the bolster, a downwardly and outwardly inclined surface carried by one end of the bridge member within one pocket, a downwardly and outwardly inclined surface carried by the other end of the bridge member within the other pocket, a wedge shoe within each of said pockets engaging the associated guide columns, two angular surfaces on each wedge shoe for engaging the inclined surface at one end of the bridge member and the inclined surface at the top of one pocket, a helical spring within the bolster engaging an intermediate portion of the bridge member at its upper end, said bridge member having an opening therein aligned with the axis of the spring, the top wall of the bolster having an opening therein aligned with the opening in the bridge member, the bottom wall of the bolster having an opening larger than the diameter of said spring, said opening in the bottom wall having slots communicating therewith, a plate closing the opening in the bottom wall of the bolster and forming a spring seat for said helical spring, lugs carried by said plate extending through said slots, each of said lugs having an opening therethrough for receiving means to maintain the plate in a position closing the opening in the bottom wall of the bolster to compress said spring and urge the bridge member upwardly, and said plate having an opening therethrough aligned with the axis of said spring.

5. In a railway car truck, a side frame having a bolster opening therein, a bolster having an end portion extending into said opening, top and bottom walls on the end portion of the bolster, said bottom wall having an opening therein, a bridge member within the bolster arranged transversely of the end portion, inclined end surfaces carried by the bridge member, inclined surfaces carried by the bolster providing pockets in the sides of the bolster, a wedge shoe in each of said pockets, a sloping surface on each shoe engaging the associated inclined surface on the

bolster, a second sloping surface on each shoe engaged by the associated inclined surface on the bridge member, a helical spring of smaller diameter than the opening in said bottom wall engaging an intermediate portion of the bridge member, a plate engaging the lower end of said spring closing the opening in the bottom wall of the bolster compressing said spring and resiliently maintaining the bridge member with the inclined end surfaces thereon in engagement with the sloping surfaces of the wedge shoes, and springs engaging the bottom wall of the bolster and said plate resiliently supporting the end portion of the bolster on the side frame and urging said plate upwardly to a position closing the opening in the bottom wall of the bolster.

6. In a railway car truck, a side frame having a bolster opening therein, a bolster having an end portion extending into said opening, top and bottom walls on the end portion of the bolster, said bottom wall having an opening therein, a bridge member within the bolster arranged transversely of the end portion, inclined end surfaces carried by the bridge member, inclined surfaces carried by the bolster, a wedge shoe at each side of the bolster, a sloping surface on each shoe engaging the associated inclined surface on the bolster, a second sloping surface on each shoe engaged by the associated inclined surface on the bridge member, a helical spring of smaller diameter than the opening in said bottom wall engaging an intermediate portion of the bridge member at its upper end, a plate engaging the lower end of said spring closing the opening in the bottom wall of the bolster compressing said spring and resiliently maintaining the bridge member with the inclined surfaces thereon in engagement with the sloping surfaces of the wedge shoes, springs resiliently supporting the end portion of the bolster on the side frame and one of said springs engaging the plate urging it to a position closing the opening in the bottom wall of the bolster, and said inclined surfaces on the bolster being at acute angles with respect to the axis of said helical spring.

7. In a railway car truck bolster stabilizer, the combination of truck side frames with bolster end receiving openings and bolster supporting springs, a bolster provided with transversely disposed pockets adjacent its ends open at opposite sides of the bolster and having openings through the bottom of the bolster; a pair of friction blocks with sloping inner ends slidably arranged in each pocket and adapted to contact the top wall of the pocket and the adjacent portion of the truck side frame; the friction blocks and a bolster side wall being formed to receive temporary means for holding the friction blocks in retracted position during assembly; hollow open bottom wedge blocks in each pocket intermediate the pair of friction blocks and having end sloping surfaces matching and in contact with the inner ends of the friction blocks, vertically disposed springs arranged in said wedge blocks for controlling the wedging relation between the wedge blocks and the friction blocks; spring supporting means for said springs arranged in the bolster bottom openings; means within the bolster for maintaining said spring supporting means in position, and means preventing rotative movement of said spring supporting means relative to the bolster.

8. In a railway car truck bolster stabilizer, a side frame provided with a bolster opening, a bolster having an end portion extending into said bolster opening, said bolster having a trans-

versely disposed pocket open at opposite sides of the bolster and having an opening through the bottom of the bolster, a pair of friction shoes with sloping inner ends slidably arranged in the pocket and adapted to contact adjacent portions of the side frame, said friction shoes and a bolster side wall being formed to receive means for holding the friction shoes in retracted positions during assembly, a wedge member in said pocket intermediate the friction shoes having end sloping surfaces in contact with the sloping inner ends of the friction shoes, a vertically disposed spring arranged under said wedge member moving it upwardly to urge the friction shoes into engagement with the side frame, a rigid member engaging the lower end of said spring arranged in the opening at the bottom of the bolster, said rigid member being formed to receive means holding it in association with the lower end of said spring during assembly, and load supporting springs carried by the side frame engaging said bolster end portion and said rigid member maintaining the same in position compressing said spring.

9. In a stabilized railway car truck, a side frame having a bolster opening, a bolster having an end portion extending into said bolster opening, said bolster having a transversely disposed pocket open at opposite sides of the bolster and having an opening through a bottom of the bolster, a pair of friction shoes with sloping inner ends slidably arranged in said pocket and adapted to contact adjacent portions of the side frame, a wedge member in said pocket intermediate the friction shoes and having end sloping surfaces in contact with the sloping inner ends of the friction shoes, a vertically disposed spring arranged under said wedge member moving it upwardly to urge the friction shoes into engagement with the side frame, a rigid member engaging the lower end of said spring arranged in the opening at the bottom of the bolster, lugs extending upwardly from diametrically opposite portions of said rigid member, said lugs being formed to receive means extending transversely within the bolster holding it in association with the lower end of said spring during assembly, and load supporting springs carried by the side frame engaging said bolster end portion and said rigid member maintaining the same in position compressing said spring.

10. In a railway car truck, a side frame having a bolster opening, a bolster having an end portion extending into said bolster opening, a bottom wall on said bolster, said bolster having a transversely disposed pocket open at opposite sides of the bolster and having an opening through said bottom wall, a pair of friction shoes having sloping inner ends slidably arranged in said pocket and adapted to contact adjacent portions of the side frame, a wedge member in said pocket intermediate the friction shoes having end sloping surfaces in contact with the sloping inner ends of the friction shoes, a vertically disposed spring arranged under said wedge member moving it upwardly to move the friction shoes into engagement with the side frame, a rigid member engaging the lower end of said spring arranged in the opening in the bottom wall of the bolster, lugs extending upwardly from said rigid member laterally of said spring having horizontally disposed openings for receiving means supported on an upper surface of said bottom wall to hold the rigid member in association with the lower end of said spring during assembly, and load supporting springs carried by the side frame engaging said bolster end portion and said rigid member

5 8 maintaining the same in position compressing said spring.

11. In a railway car truck, a side frame having a bolster opening, a bolster extending into said bolster opening, a bottom wall on the bolster, said bolster having pockets therein open at the sides of the bolster and having an opening through said bottom wall, a friction shoe arranged in each pocket for outward movement into engagement with adjacent portions of said side frame, two diverging surfaces on each friction shoe with each surface inclined with respect to a horizontal plane, a wedge member within the bolster intermediate the friction shoes, a downwardly sloping end surface on the wedge member in contact with one inclined surface of one friction shoe, a downwardly sloping end surface on the wedge member in contact with one of the inclined surfaces on the other friction shoe, an upwardly and outwardly sloping surface on the bolster within one pocket engaged by the second inclined surface on one friction shoe, an upwardly and outwardly sloping surface on the bolster within the other pocket engaged by the second inclined surface on the other friction shoe, a vertically disposed helical spring arranged under said wedge member moving it upwardly to urge the friction shoes into engagement with the side frame, a rigid member engaging the lower end of said spring arranged in the opening of the bottom wall of the bolster, and means maintaining said rigid member within said opening and compressing said helical spring.

12. In a railway car truck, a side frame having a bolster opening, a bolster extending into said bolster opening, vertically spaced horizontal walls forming a top and a bottom of the bolster, said bolster having pockets therein open at the sides of the bolster, a friction shoe arranged in each pocket for outward movement into engagement with adjacent portions of said side frame, two surfaces on each friction shoe diverging from a horizontal plane intermediate said walls, a wedge member within the bolster intermediate the friction shoes, a sloping end surface on the wedge member in contact with one surface of one friction shoe, a sloping end surface on the wedge member in contact with one of the surfaces on the other friction shoe, a sloping surface on the bolster within one pocket engaged by the second surface on one friction shoe, a sloping surface on the bolster within the other pocket engaged by the second surface on the other friction shoe, and a vertically disposed helical spring compressed between an intermediate portion of the wedge member and one of said walls moving the wedge member vertically to urge the friction shoes into engagement with the side frame.
